CONTAINER

Charles Paley, Brooklyn, N. Y.

Application December 23, 1932, Serial No. 648,602

5 Claims. (Cl. 23—258)

This invention relates to containers, and is particularly directed to a bottle for testing butter, cheese, cream, milk and the like substances for fat content.

5 An object of this invention is to provide a container or bottle of the character described, provided with a mouth or opening sufficiently large to permit lumps of viscous, solid or semi-solid material to be introduced therein and also to 10 permit the introduction of a stirring rod to either remove excess material or to stir the contents; the inlet, mouth or opening being of relatively small height and preferably merely of sufficient height for the reception of a stopper whereby the 15 stirring process may be facilitated.

The bottle is intended to be used particularly in a centrifuging process to separate the butter fat from the other substances in butter, cheese, cream, milk or the like materials, and it is an 20 object of this invention to provide a bottle of the character described adapted to be readily placed into the seat on the centrifuge apparatus and having a graduated reading tube to one side of the longitudinal axis of the bottle to provide sufficient space for a relatively large inlet opening 25 so that the materials to be tested may be readily placed directly into the body of the bottle and without the danger of the material sticking to the inner surface of the inlet.

30 A further object of this invention is to provide a bottle of the character described having a tapering shoulder portion and an inlet neck extending from said shoulder portion and provided with a stopper, the inner surface of which substantially forms a continuation of the inner surface of the shoulder to facilitate separation of the fat during the centrifuging process.

Still another object of this invention is to provide a neat, compact and durable bottle of the 40 character described, which shall be extremely economical to manufacture, simple to manipulate, attractive in appearance, and withal practical and efficient to a high degree in use.

Other objects of this invention will in part be 45 obvious and in part hereinafter pointed out.

The invention accordingly consists in the features of construction, combinations of elements, and arrangement of parts which will be exemplified in the construction hereinafter described, 50 and of which the scope of application will be indicated in the following claims.

In the accompanying drawing, in which is shown one of the various possible illustrative embodiments of this invention,

55 Fig. 1 is an elevational view of a bottle or con-

tainer embodying the invention, with parts in cross-section;

Fig. 2 is a cross-sectional view taken on line 2—2 of Fig. 1 with the stopper removed;

Fig. 3 is a view similar to Fig. 1 but showing a modified construction; and

Fig. 4 is a cross-sectional view taken on line 4—4 of Fig. 3 with the stopper removed.

Referring now in detail to the drawing, 10 designates a bottle or container embodying the 65 invention and here shown in the form of a bottle for testing butter, cheese, cream, condensed milk, ice-cream and various other products to determine the percentage of fat in said materials.

The bottle 10 may be made of glass or any 70 other suitable material and comprises preferably a body portion 11 having a bottom wall 12, a slightly upwardly and outwardly tapering conical side wall 13. The slight taper of the side wall 13 permits the body to be readily slid into the 75 usual receptacle provided for swinging the bottles in a centrifuging apparatus. The portion 13 of the bottle may be of generally circular cross-section, and extending from the upper end of said portion 13 is an inwardly tapering shoulder portion 15 from which there extends a short neck, 80 inlet or mouth portion 17 preferably offset from and parallel to the longitudinal axis of the body portion 11 of the bottle, and an elongated relatively long graduated reading tube portion 19, 85 preferably parallel to the longitudinal axis of the body 11 but offset therefrom.

In the form shown in Fig. 1 the neck 17 is substantially parallel to the tube 19 and is of larger cross-sectional area than said tube. The neck 90 17 and tube 19 may be of any suitable cross-sectional shape or diameter.

As shown in Fig. 2 of the drawing, the tube 19 and neck 17 are substantially wholly within the horizontal cross-sectional circular outline of the body 11. With this construction the bottle 10 may be readily fitted into the seat or container on the centrifuging machine.

By offsetting the graduated reading tube 19 with respect to the longitudinal axis of the body 100 11 of the bottle, the inlet neck or opening 17 may be relatively large to permit lumps of the material to be tested to be readily inserted or introduced into the bottle without smudging the inner surface of the inlet tube. Furthermore, by making the inlet tube 17 relatively short or substantially only long enough for the reception of the stopper 22, the danger of the material sticking or smudging the inner surface of the tube while being introduced into the bottle is minimized, thus 105 110 115

making for more perfect tests. Further, the provisions of a relatively large and relatively short inlet opening facilitates the use of a stirring rod which may be inserted readily through the neck 5 for the purpose of breaking up lumpy material, stirring or removing some of the contents. The stirring rod cannot be carried out with testing bottles having relatively small inlet openings, and/or relatively long inlet tubes.

10 The stopper 22, as illustrated in Fig. 1 of the drawing is provided with an inclined or tapering inner surface 23. The surface 23 substantially forms a continuation of the inner surface of the tapering portion 15 of the bottle body. Thus 15 while the bottle is swung in a centrifuging apparatus, the fats may be more readily separated since they will not be retained by the inclined surface 23 which permits free movement of the materials within the bottle without obstruction.

15 In Figs. 3 and 4 of the drawing there is shown a bottle 10a substantially similar to the bottle 10 except that the inclined shoulder 15a thereof is provided with a short inclined neck or opening 17a the axis whereof is inclined to the axis 20 of the body 11a of said bottle. The outer rim 25 of the neck 17a, however, is disposed wholly within the circular outline of the body, as shown in Fig. 4 of the drawing. The stopper 22 received within the neck 17a is likewise disposed wholly

25 within the circular horizontal outline of the body of the bottle whereby the bottle 10a may be readily inserted within the usual receptacle or seat provided for the purpose in the centrifuging machine or apparatus. The inner or bottom surface 23a of the stopper 22a is perpendicular to the axis of said stopper but nevertheless forms a substantial continuation of the inner tapering surface of shoulder 15a.

30 It will thus be seen that there is provided a device in which the several objects of this invention are achieved, and which is well adapted to meet the conditions of practical use.

35 As various possible embodiments might be made of the above invention, and as various changes 40 might be made in the embodiments above set forth, it is to be understood that all matter herein set forth or shown in the accompanying drawing is to be interpreted as illustrative and not in a limiting sense.

45 Having thus described my invention, I claim as new and desire to secure by Letters Patent:

50 1. A testing bottle comprising a body and an elongated graduated reading tube extending from said body and wholly offset from the longitudinal axis of the body of the bottle, and said body being formed with an inlet opening for introduction of material into the bottle, the axis of said opening being offset from the longitudinal axis of the body of the bottle, said reading tube and inlet opening being wholly contained within the transverse circular outline of the body of the bottle, and the

transverse circular outlines of said tube and opening being tangent to the transverse circular outline of said body.

55 2. A bottle comprising a body portion having a tapering shoulder, a graduated reading tube extending upwardly from the shoulder of said body portion and disposed parallel to and being wholly offset from the longitudinal axis of said body, and a neck extending from said body having an axis inclined with respect to the longitudinal axis of said body, a stopper within said neck having an inclined under surface substantially flush with said shoulder of said body, said reading tube, neck and stopper being wholly contained within the transverse peripheral outline of the body of the bottle, and said neck overlapping the longitudinal axis of said body.

60 3. A bottle comprising a body portion, a graduated reading tube extending from said body portion and disposed parallel to and wholly offset from the longitudinal axis of said body, and a neck extending from said body having an axis inclined with respect to the longitudinal axis of said body, a stopper within said neck at least as long as said neck, said reading tube, neck and stopper being wholly contained within the transverse peripheral outline of the body of the bottle, 65 said neck being less in length than said reading tube.

65 4. A bottle comprising a body portion having a tapering shoulder portion, a graduated reading tube extending from said shoulder portion and disposed parallel to and wholly offset from the longitudinal axis of said body, and a neck extending from said body having an axis inclined with respect to the longitudinal axis of said body, a stopper within said neck, said reading tube, neck and stopper being wholly contained within the transverse peripheral outline of the body of the bottle, 70 said neck being less in length than said reading tube, and of larger cross-sectional area than said reading tube and overlapping the longitudinal axis of said body.

75 5. A bottle comprising a body portion having a tapering shoulder portion, a graduated reading tube extending from said shoulder portion and disposed parallel to and wholly offset from the longitudinal axis of said body, and a neck extending from said body having an axis inclined with respect to the longitudinal axis of said body, a stopper within said neck, said reading tube, neck and stopper being wholly contained within the transverse peripheral outline of the body of the bottle, 80 said neck being less in length than said reading tube, and of larger cross-sectional area than said reading tube and overlapping the longitudinal axis of said body, and a stopper within said neck at least as long as said neck and having the bottom surface thereof substantially flush with said shoulder portion of said body.
